RIBBON SOAP

Charles T. Walter, Chicago, Ill., assignor to Industrial Patents Corporation, Chicago, Ill., a corporation of Delaware

Application December 8, 1937, Serial No. 178,780

1 Claim. (Cl. 87—16)

This invention relates to a new soap product.

This application is a continuation in part of my application entitled Soap product, Serial No. 92,105, filed July 23, 1936, which application 5 Serial No. 92,105 is a continuation in part of my application entitled Soap product and method of making the same, Serial No. 703,350, filed December 21, 1933.

One of the objects of the present invention 10 is to provide a new soap product of desirable form which is very readily soluble in water.

Other objects of the invention will be apparent from the description and claim which follow.

The product of the present invention is exemplified in the annexed drawing.

The preferred method of manufacturing the soap product of the present invention is to start with a hot liquid soap having a temperature of approximately 180° F. At this temperature, the 20 soap stock is a liquid and flows readily through pipes by gravity or under the influence of pump pressure.

This liquid soap stock is picked up by a suitable pump and caused to flow under pressure through 25 a suitable filter device for removing small particles of dirt or fibres which frequently find their way into the soap mixture. From the filtering device the soap stock is passed through a suitable heat exchanger which removes the sensible heat 30 and latent heat of fusion and brings about a congealing action. The temperature of the soap leaving the cooler may be any convenient desired degree, a temperature of 70° F. being satisfactory. I have found that a temperature of 90° F. permits the production of a satisfactory product.

As the soap leaves the heat exchanger, it is in 35 a stiff plastic condition. It will flow through pipes and other conduits under sufficiently great pressure. It can be forced through a fine mesh 40 filter screen in this condition, and I have found it expedient to subject the material to a secondary filtering operation at this stage in order to insure that no solid particles of substantial size remain in the mass as it flows to the forming 45 device. Any suitable forming device may be employed in producing the new ribbon soap of the present invention. A suitable extrusion device is described and claimed in my patent entitled Extrusion device, granted June 9, 1936, No. 50 2,043,682.

In forming the product of the present invention, the soap stock is passed from an extrusion device under pressure in the manner described in my patent entitled Method of making tube 55 soap, granted June 9, 1936, No. 2,043,685.

A suitable device is an extrusion device having an orifice with a central rotating breather pin. The soap stock is extruded in the form of a thin-walled tube and a vacuum of about three-fourths inch of water is drawn on the breather opening, 5 which fully collapses the tube and forms a substantially flat ribbon, which may be dried and cut into short lengths. This vacuum fully collapses the tube, and the substantially flat ribbon formed has a continuous smooth surface having arcuate 10 edges.

Obviously the ribbon would be twice as thick as the single tube from which it is prepared. Consequently, a tube with walls .0045 inch in thickness would collapse to a ribbon .009 inch 15 in thickness.

The ribbon soap may be passed through a heated extrusion nozzle in order to secure a glossy, milled appearance. In applying the 20 glossy finish, the material at the point of extrusion of the soap stock is heated to a temperature of from 160° to 180° F. The action of the heated nozzle seems to produce a very thin film of soap being heated and probably melted. The depth 25 of this heating effect is not sufficient to materially affect the strength of the finished soap ribbon. After being in contact with the cool air for a few seconds after leaving the extrusion die, the more or less molten outside film or skin 30 solidifies into a smooth, glossy surface, which is thereafter retained indefinitely.

An extrusion die nozzle may be heated by means of a hot water jacket around its lower end, which provides sufficient heat to the apparatus 35 to compensate for the heat removed by the flowing stream of soap passing through such a device. If the soap stock is extruded at atmospheric temperature, a suede finish common in soap products is secured. If the soap stock is one containing filler, the heat treatment develops in the 40 finished product a gloss like that of milled soap not containing filler.

After the ribbon soap is formed, it is received upon a drying conveyor, which may be of the type shown in my patent entitled Drier conveyor, 45 granted June 9, 1936, No. 2,043,681. After the ribbons are partially dried, they are passed through a cutting device which may consist of a plain roller having a smooth machined surface adapted to engage with a second roller carrying 50 a series of knife edges. From this cutting device the soap ribbons are discharged in the form of small, short ribbon like elements, which upon completion of drying are ready for packaging.

The present invention is concerned with rela- 55

- tively thin ribbons, that is, ribbons having a thickness of the order of below .18 inch. The preferred thickness is .09 inch. The preferred length of ribbons which make up the mass is from one-fourth inch to five-eighths inch.
- The ribbon soap product produced in accordance with the present invention is made of component particles which are collapsed soap tubes with a continuous smooth surface, having arcuate edges. The component particles are sufficiently large to readily appear to the eye as individually distinct particles of reasonably uniform size and shape, and sufficiently small to constitute necessarily a bulk soap product of such character that the component particles are used in mass rather than as separate entities, and consist of a collapsed soap tube solidified into a characteristic arcuate edged ribbon, whereby chipping at the edges and the consequent production of dust-like matter is obviated, in which product the individual particles comprise appreciable amounts of soap, so that the respective particles are individually distinct bodies, capable of ready, independent, relative movement and readily separated upon introduction into water. The particles are capable of attaining practically immediate contact with water upon being dropped upon the surface thereof, and of maintaining their independent identity without sticking together to form masses of undissolved soap. The individual particles are large considering the amount of soap contained therein, and they thereby present an available surface area which is large relative to the amount of soap in the particle, whereby the soap product is free from any substantially characterizing amount of powder or dust-like matter, is soluble with particular readiness, speed, and completeness, and is char-

acterized by a total absence of any tendency to form lumps, balls, or spots of soap undissolved in washing.

I claim:

A ribbon soap product in which the component particles are collapsed soap tubes with a continuously smooth surface, having arcuate edges, sufficiently large to readily appear to the eye as individually distinct particles of reasonably uniform size and shape, and sufficiently small to constitute necessarily a bulk soap product of such character that the component particles are used in mass rather than as separate entities, and consist of a collapsed soap tube solidified into a characteristic arcuate edged ribbon, whereby chipping at the edges and the consequent production of dust-like matter is obviated, in which product the individual particles comprise appreciable amounts of soap so that the respective particles are individually distinct bodies capable of ready, independent, relative movement and ready separation upon introduction into water, are capable of attaining practically immediate contact with water upon being dropped upon the surface thereof, and of maintaining their independent identity without sticking together to form masses of undissolved soap, and are large considering the amount of soap contained therein to thereby present an available surface area which is large relative to the amount of soap in the particle, whereby the soap product is free from any substantial characterizing amount of powder or dust-like matter, is soluble with particular readiness, speed and completeness, and is characterized by a total absence of any tendency to form lumps, balls or spots of undissolved soap in washing.

CHARLES T. WALTER.
